UNITED STATES PATENT OFFICE.

MORRIS URI BERNHEIM, OF LOUISVILLE, KENTUCKY, ASSIGNOR, BY MESNE ASSIGNMENTS, TO THE ALVEY-FERGUSON COMPANY, OF OAKLEY, CINCINNATI, OHIO, A CORPORATION OF OHIO.

CONVEYER.

1,086,886.

Specification of Letters Patent. Patented Feb. 10, 1914.

Application filed May 13, 1909. Serial No. 495,706.

To all whom it may concern:

Be it known that I, MORRIS URI BERNHEIM, a citizen of the United States, residing at Louisville, in the county of Jefferson 5 and State of Kentucky, have invented certain new and useful Improvements in Conveyers, of which the following is a specification.

This invention relates to certain improvements in conveying systems of the type, speaking generally, wherein a vertical elevator is employed in conjunction with means for feeding thereto and therefrom the goods which are to be transported thereby.

Many systems of this kind have been proposed, but hitherto none of them have been capable of delivering to the elevator and conveying therefrom, in an entirely automatic manner and with absolute certainty, 10 boxes and similar things of various sizes and kinds and of different or ordinary constructions and sizes, such as are handled in bottling houses, packing houses, warehouses, etc., and, consequently which do not themselves form a part of the conveying system.

The principal aim of my invention is to provide a system embodying a vertical elevator and feeding devices so related to each other that boxes and other packages, forming 15 no part of the conveying system and of ordinary construction, such as are handled in bottling houses, packing houses, etc., will be picked up by the elevator, transported thereby to the floor for which it is intended 20 and at the latter place be picked up from the elevator and carried off to the place at which it is to be discharged, all with certainty and entirely automatically except for the incidental adjustment of a certain part 25 and at the latter place be picked up from the elevator and carried off to the place at which it is to be discharged, all with certainty and entirely automatically except for the incidental adjustment of a certain part

30 or parts to permit the packages to pass by the same, whereby important purposes are subserved which have not been accomplished by any apparatus or system of this type hitherto proposed. This principal aim of 35 the invention is accomplished by means of a system, such as that herein disclosed as exemplary of what I now regard to be the best form thereof, wherein there is essentially employed, (1) vertically, or approxi- 40 mately vertically, traveling members, (2) a plurality of platforms pivotally suspended therefrom, having lateral openings there- 45 through, (3) horizontally, or approximately horizontally, arranged feed or discharge 50 members projecting into the planes of said

openings, and having endless traveling package-conveying means, and (4) means for intermittently moving said endless traveling package-conveying means during the intervals between the periods when said platforms pass the feed members. 60

The invention consists broadly in this combination of elements, and, further, in certain peculiarities in the construction and arrangement of parts, and in certain other 65 novel combinations of elements, all substantially as hereinafter described and particularly pointed out in the subjoined claims.

In the accompanying drawings illustrating the preferred embodiment of my invention:—Figure 1 is a side elevation, shown somewhat diagrammatically, of a system embodying my improvements. Fig. 2 is a detail view of one of the feeders or dischargers and its actuating means, including a part of the elevator, drawn to a larger scale than Fig. 1. Fig. 3 is a plan view of the parts represented in Fig. 2, and which would appear below the plane of the line 3—3, Fig. 1, for example. Fig. 4 is a section on line 4—4 of Fig. 3. Fig. 5 is a detail side view showing a different form of feeder or discharger which may be employed and Fig. 6 is a plan view of the form represented in Fig. 5. Fig. 7 is a side elevation of a pair of feeders or dischargers, which may be employed. Fig. 8 is a detail view intended more particularly to show the beveled interengaging faces of the means for operating the clutch 43; and Fig. 9 is a view of the upper end of the elevator, with parts broken away, particularly intended to show the correlation of parts when a platform is passing from its ascending to its descending course of travel. 95

The same characters of reference designate the same parts in the several views.

For convenience in explaining the invention I will state that it comprises a member, designated generally by the character A, which travels in a vertical plane; a plurality or series of platforms, designated generally by the reference character B, which travel with said member and have lateral openings; feed or discharge members, designated generally by the character C, which are arranged in horizontal or approximately horizontal plane and intersect the plane of movement of the packages on the carrier, said feed or discharge members having endless traveling package-conveying 105 110

means, and means designated generally by the character D, for intermittently moving the endless traveling package-conveying means of the feed or discharge members 5 during the intervals between the periods when the platforms pass said members.

While other constructions than those herein set forth may be employed, without departing from the spirit of the invention 10 or the scope of the subjoined claims, yet the particular constructions herein illustrated and described most effectively lend themselves to, and combine with each other in the production of the important purposes 15 which I have in view, and, therefore, are made the subject of claims which are more and less restricted thereto.

Referring now to the forms of the invention exemplified by the drawings, I would 20 call attention to the fact that the member A forms the platform-carrying part of a vertical or straight lift elevator. This elevator has its frame composed of uprights 1 arranged in the four corners thereof, as 25 usual. These uprights extend from top to bottom of the elevator and are suitably connected with each other and braced, as by transverse members 2 arranged at proper intervals.

30 The members A referred to consists of a pair of chains 5 and 6 which run over sprockets 7 and 8 suitably supported at the top and bottom of the elevator. To the shaft of one of the sprockets, as 7, a driving motor 9 of any suitable kind is connected.

Each of the uprights 1 is preferably made of angle irons arranged to form guides for the chain which runs therein.

40 Each of the platforms B is provided with a pair of vertically extending arms 10, the lower portions of which are connected with each other by a transverse bar 11 which supports a plurality of fingers 12 which extend forward and rearward therefrom, and are adapted to carry boxes, barrels, bags and other packages to be elevated. These fingers are separated from each other by spaces 13 which constitute lateral openings 45 formed in the platform. The platform is arranged between the pair of chains 5 and 6 and each of its upwardly extending arms 10 is carried by a stub shaft 14 which in turn is carried by the contiguous chain, 5 50 or 6. These parts are so correlated that the platform is pivotally suspended from the pair of traveling chains and connects said chains with each other.

55 Pendent from the opposite sides of each platform is a pair of rollers 15 which run in the channels of the contiguous frame members 1 and by their engagement with the walls thereof serve to restrict the lateral vibration of the pivotally suspended 60 platforms, with a minimum of friction.

These rollers are here shown as carried by extensions 10^a of the arms 10, though they may be supported in other ways, if desired.

At the top of the elevator, arched or convexly-curved fixed straps 16 are arranged. 70 They extend from the front side to the rear side of the elevator, that is to say, from its receiving to its delivering side, in position to form tracks upon which the rollers 15 run while passing from the receiving to the 75 delivering side of the elevator.

In practice, there is employed a series of the platforms referred to, supported and guided in the manner referred to.

The elevator may be made of any desired height and to extend, if necessary, from the bottom to the top of a building of any height, through openings in the floors of said building. This is clearly shown in 80 Fig. 1, in which the several floors of a building are designated by the characters 100-104, inclusive, and the openings therein are designated by the characters 85 101^a-104^a, inclusive. On each of said floors there is arranged a gravity conveyer, or a 90 suitable system of conveyers, X, which feeds the packages toward the receiving side of the elevator, and on each floor there is also a gravity conveyer, or a suitable system of conveyers, Y, which leads off from 95 the delivering side of the elevator. These 100 conveyers may be of any suitable construction and length, and they may be composed of variously arranged runs, according to the varying requirements of particular installations. As they are well known in the art, and as particular details thereof are not essential to the present invention, it is unnecessary to disclose them in detail herein.

The number of platforms employed and their distance from each other, depends upon the height of the elevator and the particular requirements as to the capacity which the elevator should answer, and may be varied, as desired. 105

Between each of the conveyers X and Y and the contiguous side of the elevator the before-mentioned approximately horizontal feed and discharge members C are arranged. These members practically form continuations of the respective conveyers. They may be slightly inclined to an extent corresponding with the grade of the gravity conveyers, as shown in Fig. 1, in which they are shown as approximately though not exactly horizontal, or they may be truly horizontal, as shown in other figures. The feed members shown on the right hand side in Fig. 1, serve to deliver the packages from the conveyers X, to the elevator, while the discharge members shown on the left hand side of said figure, serve to deliver the packages from the elevator to the conveyers Y. 115 120 125

Each of the feeding members is characterized by the fact that it crosses the plane 130

of travel of the platforms B and has portions which register with the openings 13 between the forwardly and rearwardly extending fingers 12 when the latter are in position to receive or deliver packages, and also has longitudinal openings through which said fingers pass and a transverse space which permits passage of the cross bar 11 of the platforms. They are also provided 5 with intermittently moved package-carrying and feeding devices, which are located on one or both sides of the transverse space in each feeding or discharging member, as preferred. The correlation of these parts is 10 such that the portion of each feeding or discharging member in front of its said transverse space coöperates with the forwardly extending portion of the fingers of the platform while the portion rearward of said 15 space coöperates with the rearwardly extending parts of said fingers, in the transfer of the packages to or from the platform, and further is such that the packages are fed to the elevator from the gravity conveyer, 20 or from the elevator to the gravity conveyer, by the intermittently-moved feeding devices, whose movements are so timed as to assure proper delivery of the packages to or from 25 the platforms.

30 Various means exemplifying what I regard as suitable for the purposes are shown in the accompanying drawings.

In the form shown best in Figs. 2, 3 and 4, the feeding or discharging member is composed of four separated sections 25, 25 and 35, 35. The sections 25 are located on one side of the vertical plane traversed by the cross bars 11 and in position to be between the forwardly-extending parts of the fingers 40 12, while the sections 35 are located on the other side of said vertical plane and in position to be between the rearwardly-extending parts of said fingers. Said feeding or discharging member thus is provided with 45 longitudinal openings 26 and 27 and with a transverse opening 28. The endless traveling package conveying device, in this form is a chain 29 extending over sprockets 30 and 30^a and provided with rollers 31 which run 50 upon a floor 32 having a track 32^a therefor. This causes the rollers to rotate on their own axes while they are being moved bodily by the chains. The package rests upon these rollers and in addition to being moved with 55 the chains, is fed forward on the rollers by the rotation of the latter. The package therefore travels at a speed greater than that of the chains, whereby it moves a greater distance in a given length of time than 60 otherwise. The tracks 32^a by their frictional resistance to the rollers stop the rotation of the latter upon the conclusion of their traveling movement and thus cause movement of the package on the rollers to cease. The 65 feeding movement of the package to the ele-

vator is timed to end at or before a platform reaches a feeder, and, similarly, the movement of the discharger at the other side of the elevator is timed to commence when a platform has passed by the same and has 70 deposited its package thereon.

The means (D) which I prefer for transmitting intermittent movement to the traveling chains of each of the feed and discharge members comprises a pair of shafts 75 36 and 36^a which are provided with sprockets 37 and 38. These sprockets 37 and 38 engage an endless chain 39, the working stretch of which is parallel to the contiguous elevator chain and is of any suitable 80 length. Each chain 39 is operated intermittently from the adjacent continuously moving platform-carrying chain of the elevator, through the medium of a suitable part or parts which derive movement from 85 the latter chain. In the present exemplification of the invention, the chains 39 are provided with spaced projections 40 (there being a plurality of such projections from each chain 39) which extend into the path 90 of the rollers 15. As said rollers 15 partake of the traveling movement of the platform-carrying chains and are arranged immediately below the platforms, it will be apparent that each of the chains 39 which is 95 associated with a feeder will be operated during the ascending movement of each platform, whereby the endless conveyer of each feeder will operate to feed a package positively into position to be taken up by 100 the next succeeding platform; while each of the chains 39 associated with a discharger will similarly be operated during the descending movement of each platform to operate the endless conveyer of each discharger to positively carry the package off as soon as the package has been deposited on said conveyer. This intermittent movement is communicated to the chains 29 by 105 suitable means. As herein shown, the before mentioned sprockets 30 of the chains are mounted on a shaft 300 upon which is mounted a sprocket 41 which engages a chain 42, which runs over a sprocket 41^a on the shaft 36 of the actuating means, and 110 hence transmits movement to the chains 29. 115

In practice, a feeding device and a discharging device are preferably located at opposite sides of the elevator on each floor and provision must be made for adjusting 120 to an inoperative position those which are not being used to deliver packages to or receive packages from the elevator. To this end the sections 25 are each fixed to their shaft 300 which acts as a pivot upon which they may be turned up, or otherwise suitably mounted so that they may be turned out of the path of the platforms as indicated by dotted lines in Fig. 1.

125 In order that traveling movement may 130

not be transmitted to the chains of the feeders or dischargers at this time, means are provided whereby the latter are automatically disconnected from their actuating mechanism while the feeder or discharger which carries them is being adjusted to inoperative position. A suitable means for this purpose embodies a clutch 43 which is interposed between the sprocket 41 and the 10 shaft 300 and has its movable member keyed upon the shaft and moved to and from its companion by a spring-pressed angle arm 44 having a beveled face 45 which is engaged by an actuating element 46 having a correspondingly beveled face 46^a, the parts being so correlated that the arm 44 will be retracted to correspondingly retract the movable member of the clutch from its companion while the feed member 26 is being 20 turned out of the path of the carriers, and advanced to reengage the movable clutch member with its companion while said feed member is being moved into the path of travel of said carriers. When in its raised 25 position the feed member acts as a stop to the progress of any packages thereonto from the gravity way.

In the form shown in Figs. 2, 3 and 4, each frame section 35 is provided with 30 freely-rotatable rollers 35^a onto which the packages are fed by the traveling package-carrying and feeding devices on the sections 25. This forms a simple means which may be desirable in many cases. At the end of 35 each of these sections a stop 35^b is provided to prevent the packages from traveling beyond the same. The ends of these sections are pivotally mounted on a shaft 35^c whereby they may be turned up into inoperative 40 position, indicated by dotted lines in Fig. 1. In some cases however it will be preferred to have the sections rearward of the transverse platform bar 11, as well as those forward thereof, provided with traveling package feeding devices, as indicated in the remaining figures of the drawings. In the form shown in Figs. 5 and 6 said devices are identical with those already described, being merely repeated in the sections 350 corresponding to the sections 35 of the previous 50 form. The shaft 351 of this device is driven by a chain-mechanism which is a duplicate of that which has been already described and is shown at the right hand of this figure, and also includes the clutch mechanism set forth. Further description is therefore, believed to be unnecessary.

In the form shown in Fig. 7 endless belts 290 and 291 are substituted for the feeding 60 chains 29 and 350 of the previously described forms. It will be apparent that freely rotatable rollers, such as those numbered 35^a already described, may be used in this form in lieu of the inner belts 291.

Having now described the invention what

I believe to be new and desire to secure by Letters Patent, is:

1. A conveyer comprising a vertically traveling member, a series of platforms pivotally suspended therefrom and having lateral openings, approximately horizontal members projecting into the planes of said openings and provided with endless traveling package-carrying means, and means whereby said endless-traveling package-carrying means are automatically moved intermittently at predetermined times with relation to the movement of the platform to positively convey packages relatively to said platforms. 70

2. A conveyer comprising vertical endless travelers, a plurality of platforms pivotally suspended therefrom and having lateral openings, an approximately horizontal feeder operatively related to the ascending platforms, a discharger operatively related to the descending platforms, each said feeder and discharger having an endless traveling package-carrying means, means whereby the endless traveling package-carrying means of the feeder is moved intermittently from the vertical endless traveler, to positively carry a package into a plane which is intersected by the plane of travel of the ascending platforms, and means for intermittently moving the endless-traveling package-conveying means of the discharger from the vertical endless traveler, to positively carry a package deposited thereon by a descending platform away from the plane 90 of travel of the descending platforms. 95

3. In a conveyer system, an elevator provided with package carriers having forwardly and rearwardly projecting parts, combined with a feeding or discharging means therefor adapted to permit the carriers to pass and having two complementary portions so arranged as mutually to support a package in the plane of travel of the carrier and respectively coöperating with the forwardly and rearwardly projecting parts thereof in the transfer of the packages, one of said portions of the feeding or discharging means having traveling rollers which engage the packages and means for causing 110 said rollers to rotate while they are traveling. 115

4. In a conveyer system, an elevator provided with package carriers having forwardly and rearwardly projecting parts, combined with a feeding or discharging means therefor adapted to permit the carriers to pass and having two complementary portions so arranged as mutually to support a package in the plane of travel of the carrier and respectively coöperating with the forwardly and rearwardly projecting parts thereof in the transfer of the packages, each of said portions of the feeding or discharging means having rollers which engage the 120 125 130

packages and means whereby the rollers of one of said portions are caused to travel intermittently.

5. In a conveyer system, an elevator provided with package carriers having forwardly and rearwardly projecting parts, combined with a feeding or discharging means therefor adapted to permit the carriers to pass and having two complementary portions so arranged as mutually to support a package in the plane of travel of the carrier and respectively coöperating with the forwardly and rearwardly projecting parts thereof in the transfer of the packages, each 10 of said portions of the feeding or discharging means having rollers which engage the packages, the rollers of one of said portions having means for causing them to travel and means for causing them to rotate while they 15 are traveling.

6. In a conveyer system, an elevator provided with package carriers having forwardly and rearwardly projecting parts, combined with a feeding or discharging 20 means therefor adapted to permit the carriers to pass and having two complementary portions so arranged as mutually to support a package in the plane of travel of the carrier and respectively coöperating with the forwardly and rearwardly projecting parts thereof in the transfer of the packages, one 25 of said portions of the feeding or discharging means having endless traveling means for feeding the packages thereon and means 30 for imparting intermittent movement to said 35 endless traveling means.

7. In a conveyer system, an elevator provided with package carriers having forwardly and rearwardly projecting parts and 40 continuously movable means which carry the same, combined with a feeding or discharging means, adapted to permit the carriers to pass and having two complementary portions so arranged as mutually to support a package in the plane of travel of a carrier and respectively coöperating with the forwardly and rearwardly extending portions thereof in the transfer of the package, one 45 of said portions of the feeding or discharging means having endless package-conveying means and means actuated by the 50 movable means of the elevator for imparting intermittent movement to the package conveying means of the feeding or dis- 55 charging means.

8. In a conveyer system, an elevator provided with package-carriers having forwardly and rearwardly projecting parts and continuously movable means which carry 60 the same, combined with a feeding or discharging means, adapted to permit the carriers to pass and having two complementary portions so arranged as mutually to support a package in the plane of travel of a carrier and respectively coöperating with the 65

forwardly and rearwardly extending portions thereof in the transfer of the package, each of said portions of the feeding or discharging means having package-supporting rollers, and one of said portions having means intermittently actuated by a continuously-movable part of the elevator for imparting intermittent travel to its said rollers. 70

9. In a conveyer system, an elevator provided with package-carriers having forwardly and rearwardly projecting parts and continuously movable means which carry the same, combined with a feeding or discharging means, adapted to permit the carriers to pass and having two complementary portions so arranged as mutually to support a package in the plane of travel of a carrier and respectively coöperating with the forwardly and rearwardly extending portions thereof in the transfer of the package, each 75 of said portions of the feeding or discharging means having package-supporting rollers, and means intermittently actuated by a continuously-movable part of the elevator for imparting intermittent travel to said 80 rollers. 85

10. In a conveying system, an elevator provided with package-carriers having forwardly and rearwardly projecting parts, a feeding or discharging means therefor comprising a plurality of spaced separated sections relatively arranged to permit the carriers to pass and mutually to support a package in the plane of travel of said forwardly and rearwardly projecting parts 95 thereof, one of said sections having an endless traveling package conveying means, and means for moving said package conveying means intermittently and automatically at predetermined times in the travel of the 100 carriers relatively thereto. 105

11. In a conveyer system, an elevator provided with package-carriers having forwardly and rearwardly projecting parts, a feeding or discharging means therefor comprising a plurality of spaced separated sections relatively arranged to permit the carriers to pass and mutually to support a package in the plane of travel of said forwardly and rearwardly projecting parts 110 thereof, each of said sections having package-supporting rollers, and means for imparting traveling movement to the rollers of the sections which coöperate with the forwardly projecting parts of the carriers. 115

12. In a conveyer system an elevator provided with package-carriers having forwardly and rearwardly projecting parts, a feeding or discharging means therefor comprising a plurality of spaced separated sections relatively arranged to permit the carriers to pass and mutually to support a package in the plane of travel of said forwardly and rearwardly projecting parts 125 thereof, each of said sections having pack- 130

age-supporting rollers, and means for imparting intermittent traveling movement to the rollers of the sections which coöperate with the forwardly projecting parts of the carriers.

13. In a conveyer system an elevator provided with package carriers having forwardly and rearwardly projecting parts, a feeding or discharging means therefor comprising a plurality of spaced separated sections relatively arranged to permit the carriers to pass and mutually to support a package in the plane of travel of said forwardly and rearwardly projecting parts

14. In a conveyer system, an elevator comprising a plurality of spaced sections relatively arranged to permit the carriers to pass and mutually to support a package in the plane of travel of said forwardly and rearwardly projecting parts thereof, each of said sections having package-supporting rollers, and means for imparting intermittent traveling movement to the rollers of the sections which coöperate with the forwardly projecting parts of the carriers.

15. In a conveyer system, an elevator comprising a plurality of spaced sections relatively arranged to permit the carriers to pass and mutually to support a package in the plane of travel of said forwardly and rearwardly projecting parts thereof, each of said sections having package-supporting rollers, and means for imparting intermittent traveling movement to the rollers of the sections which coöperate with the forwardly projecting parts of the carriers including an actuating element which is operated by a continuously-moving part of the elevator.

16. In a conveyer system, an elevator provided with package carriers having forwardly and rearwardly projecting parts, combined with feeding or discharging means therefor adapted to permit the carriers to pass and having two complementary portions so arranged as mutually to support a package in the plane of travel of the carrier and respectively coöperate with the forwardly and rearwardly projecting parts thereof in the transfer of the packages, one of said portions being movable into and out of operative position and having a traveling package-feeding or discharging element thereon, means whereby said element is operated from the said traveling means of the elevator, including a clutch, and means whereby the elements of the clutch are automatically disconnected from each other in the movement of the feeder or discharger to inoperative position and are automatically connected with each other in the movement of the feeder or discharger to operative position.

17. In a conveyer system, an elevator provided with package carriers having forwardly and rearwardly projecting parts, and provided with traveling means which carry the same combined with feeding or discharging means therefor adapted to permit the carriers to pass and having two complementary portions so arranged as mutually to support a package in the plane of travel of the carrier and respectively coöperate with the forwardly and rearwardly projecting parts thereof in the transfer of the packages, one of said portions being movable into and out of operative position and having a traveling package-conveying element thereon, means whereby said element is operated by the elevator, and means automatically operated to disconnect said element from its actuating part of the elevator when the feeding or discharging portion which carries it is in inoperative position.

18. In a conveyer system, an elevator provided with package carriers having forwardly and rearwardly projecting parts, and provided with traveling means which carry the same combined with feeding or discharging means therefor adapted to permit the carriers to pass and having two complementary portions so arranged as mutually to support a package in the plane of travel of the carrier and respectively coöperate with the forwardly and rearwardly projecting parts thereof in the transfer of the packages, one of said portions being movable into and out of operative position and having a traveling package-conveying element thereon, means whereby said element is operated from the said traveling means of the elevator, and means whereby the traveling means of the elevator and the traveling means of the feeder or discharger are automatically disconnected from each other when the latter is in inoperative position.

19. In a conveyer system, an elevator provided with package carriers having forwardly and rearwardly-projecting parts, and provided with traveling means which carry the same combined with feeding or discharging means therefor adapted to permit the carriers to pass and having two complementary portions so arranged as mutually to support a package in the plane of travel of the carrier and respectively coöperate with the forwardly and rearwardly-projecting parts thereof in the transfer of the packages, one of said portions being movable into and out of operative position and having a traveling package-feeding or discharging element thereon, means whereby said element is operated from the said traveling means of the elevator, including a clutch, and means whereby the elements of the clutch are automatically disconnected from each other in the movement of the feeder or discharger to inoperative position and are automatically connected with each other in the movement of the feeder or discharger to operative position.

20. In a conveyer system, an elevator provided with package carriers having forwardly and rearwardly-projecting parts, and provided with traveling means which carry the same combined with feeding or discharging means therefor adapted to permit the carriers to pass and having two complementary portions so arranged as mutually to support a package in the plane of travel of the carrier and respectively coöperate with the forwardly and rearwardly-projecting parts thereof in the transfer of the packages, one of said portions being movable into and out of operative positions and having a traveling package-conveying element thereon, means whereby said element is operated from the said traveling means of the elevator, including a clutch, and an arm which acts on one member of the clutch and is provided with a spring for moving it in one direction and means for moving it in the other direction, to automatically disconnect said member of the clutch from its companion in the movement of the feeder or discharger to inoperative position and automatically re-connect the same in the movement of the feeder to operative position.

21. In a conveyer system, an elevator provided with endless traveling elements and package-carrying platforms carried thereby, combined with feeders or dischargers spaced apart along the length of the elevator, on the receiving and discharging sides thereof and extending into the plane of travel of the platforms, traveling means on the feeders or dischargers and means actuated from said endless traveling elements for intermittently moving the traveling means on the feeders or dis-

chargers during the intervals between the periods when the platforms pass the same.

19. In a conveyer system, an elevator provided with endless traveling elements and package carrying platforms carried thereby and provided with forwardly and rearwardly extending elements, combined with feeders and dischargers spaced apart along the length of the elevator, on the receiving and discharging sides thereof, and extending into the plane of travel of the platforms and adapted to permit the platforms to pass, each feeder and discharger having complementary portions which respectively coöperate with the forwardly and rearwardly extending elements of the platform, traveling means on the feeders and dischargers and means actuated from the endless traveling elements of the elevator for intermittently moving the traveling means on the feeders and dischargers during the intervals between the periods when the platforms pass the same.

20. In a conveying system, an elevator provided with a package-carrying platform, combined with a package conveyer arranged on the receiving side of the elevator and comprising two complementary portions which mutually intersect the plane of travel of the platform, each of said portions having package conveying rollers, and means whereby intermittent traveling movement is imparted to the rollers of one of said portions at a predetermined time in the travel of the platform.

21. In a conveyer system, an elevator provided with package carrying platforms, combined with a means arranged at the discharge side of the elevator and comprising two complementary portions mutually intersecting the plane of travel of the platform and each provided with package conveying rollers, the rollers of the outer of said portions provided with means for causing the same to travel when a package has been deposited thereon by a platform.

22. In a conveyer system, an elevator provided with package carrying platforms, combined with a means arranged at the discharge side of the elevator and comprising two complementary portions mutually intersecting the plane of travel of the platform and each provided with package feeding rollers, the rollers of the outer of said portions being provided with means for causing the same to travel when a package has been deposited thereon by a platform, the latter means comprising endless traveling chains connected to the rollers, and means connected with said chains for actuating the same intermittently.

23. In a conveyer system, an elevator provided with package carrying platforms, combined with a means arranged at the discharge side of the elevator and comprising

two complementary portions mutually intersecting the plane of travel of the platform and each provided with package feeding rollers, the rollers of the outer of said portions provided with means for causing the same to travel when a package has been deposited thereon by a platform, the latter means comprising endless traveling chains connected to the rollers, and means connected with said chains for actuating the same intermittently, having an actuating element which is intermittently operated by a moving part of the elevator.

24. In a conveyer system, an elevator provided with a continuously movable endless traveling means and a package carrier carried thereby, combined with a feeder or discharger which intersects the plane of movement of the package on said carrier, said feeder or discharger having a traveling element, and means for moving said traveling element intermittently comprising an endless traveling means arranged alongside a run of the endless traveling means of the elevator, a device projecting from one of the endless traveling means into the plane of travel of a part movable with the other throughout a portion of its travel, for imparting intermittent motion to the endless traveling means of the actuating means of the feeder or discharger, and means for transmitting said movement to the traveling element of the feeder.

25. In a conveyer system, an elevator having a continuously-movable endless traveling element provided with package-carriers, an endless traveling chain arranged alongside a run thereof and parallel therewith throughout a portion of the length of the latter, projections extending from one of said parts into the plane of travel of a part movable with the other for imparting intermittent movement to said chain, a feeder or discharger which intersects the plane of movement of the packages on the carriers and is provided with a traveling element, and means for transmitting intermittent movement from the chain to the last-mentioned traveling element.

26. In a conveyer system, an elevator having a continuously-movable endless traveling element provided with package-carriers, an endless traveling chain arranged alongside a run thereof and parallel therewith throughout a portion of the length of the latter, a plurality of spaced projections extending from said chain and intermittently engaged one after the other by a part movable with the traveling element of the elevator, a feeder or discharger having a traveling element and means for transmitting intermittent movement from the chain to the last-mentioned traveling element, said feeder or discharger intersecting the plane of movement of the packages on the carriers.

27. In a conveying system an elevator comprising a vertically traveling member having a package-carrying platform which is pivotally suspended therefrom and provided with lateral openings, a gravity conveyer arranged on one side of said elevator and with its end spaced therefrom, and a member operatively related to said end of the gravity conveyer and projecting into the plane of said opening, said member having an endless traveling means which conveys the package between the gravity conveyer and elevator and means for intermittently moving its said endless means during the intervals between the periods when the platforms pass the same.
28. In a conveying system, an elevator comprising endless devices, means whereby said devices are caused to travel in an approximately vertical direction, package-carrying platforms which are pivotally suspended from said devices and have lateral openings, a gravity conveyer arranged on one side of said elevator with its end spaced therefrom, a member arranged in the space between the gravity conveyer and elevator and projecting into the plane of said openings, said member having traveling package conveying means arranged approximately in the plane of the bed or way of the gravity conveyer, and means for imparting intermittent movement to said traveling package-conveying means from the endless devices of the elevator.
29. In a conveying system, an elevator comprising endless devices, means whereby said devices are caused to travel in an approximately vertical direction, package-carrying platforms which are pivotally suspended from said devices and have lateral openings, a gravity conveyer arranged on one side of said elevator with its end spaced therefrom, a member arranged in the space between the gravity conveyer and elevator and projecting into the plane of said openings, said member having endless traveling package-conveying means arranged approximately in the plane of the bed or way of the gravity conveyer, endless traveling means having spaced projections arranged to be operated from the first-mentioned endless devices, and means connecting said endless traveling means with said package-conveying means for imparting intermittent movement to the latter at predetermined times in the travel of the endless traveling devices of the elevator.
30. In a conveying system, an elevator comprising a vertically traveling member having a package-carrying platform which is pivotally suspended therefrom and provided with lateral openings, a gravity conveyer arranged on one side of the elevator with its end spaced therefrom, a member arranged in the space between the gravity

conveyer and elevator and projecting into the plane of said openings, said member having package-conveying rollers which are arranged approximately in the plane of the bed or way of the gravity conveyer and means whereby said rollers are caused to rotate and to travel relatively to the platform at predetermined times in the movement of the latter.

31. In a conveying system, an elevator provided with package carrying platforms having forwardly and rearwardly projecting parts, a gravity conveyer arranged on one side of said elevator with its end spaced therefrom, and a member arranged in the space between the gravity conveyer and elevator, said member being adapted to permit the platforms to pass and having two complementary portions so arranged as mutually to support a package in the plane of travel of the platforms and respectively cooperating with the forwardly and rearwardly projecting parts of the latter in the transfer of the packages, one of said portions of said means having endless traveling means arranged approximately in the plane of the bed or way of the gravity conveyer, and means whereby intermittent movement is given thereto from a moving part of the elevator.

32. In a conveying system, an elevator provided with package carrying platforms having forwardly and rearwardly projecting parts, a gravity conveyer arranged on one side of said elevator with its end spaced therefrom, and a member arranged in the space between the gravity conveyer and elevator, said member being adapted to permit the platforms to pass and having two complementary portions so arranged as mutually to support a package in the plane of travel of the platforms and respectively cooperating with the forwardly and rearwardly projecting parts of the latter in the transfer of the packages, each of said portions having rollers and means for causing the rollers of one of said portions to rotate and travel intermittently, said means including elements whereby said traveling movement is given from a moving part of the elevator.

33. In a conveying system, an elevator comprising endless devices, means whereby said devices are caused to travel in an approximately vertical direction, package carrying platforms which are pivotally suspended from said devices and have lateral openings, a gravity conveyer arranged on one side of said elevator with its end spaced therefrom, a member arranged in the space between the gravity conveyer and elevator and projecting into the planes of said openings of the platforms, said member having package conveying rollers which are arranged approximately in the plane of the

bed or way of the gravity conveyer, and means for imparting intermittent traveling and rotative movement to said rollers at predetermined times in the travel of the endless

5 traveling devices of the elevator, said means including connections whereby said traveling movement is given the rollers from said endless traveling devices of the elevator.

34. In a conveying system, an elevator 10 comprising a vertically traveling member having package carrying platforms which are pivotally suspended therefrom and are provided with lateral openings, gravity conveyers arranged on opposite sides of said elevator with their ends spaced therefrom, a feed member and a discharge member respectively arranged between the gravity conveyers and the elevator and projecting into the planes of said openings, each of said 15 members having endless traveling package conveying means which are arranged approximately in the planes of the beds or ways of their respective gravity conveyers and means whereby said endless traveling 20 means are caused to travel intermittently at predetermined times in the movement of the platforms.

35. In a conveying system, an elevator 25 comprising a vertically traveling member having package carrying platforms which are pivotally suspended therefrom and are provided with lateral openings, gravity conveyers arranged on opposite sides of said elevator with their ends spaced therefrom, a feed member and a discharge member respectively arranged between the gravity conveyers and the elevator and projecting into the planes of said openings, each of said members having endless traveling package

conveying rollers and means whereby said 40 rollers are caused to travel intermittently and to rotate while traveling, said means including connections for giving traveling movement to the rollers from a moving part of the elevator. 45

36. In a conveying system, an elevator comprising a vertically traveling member having package-carrying platforms which are pivotally suspended therefrom and are provided with forwardly and rearwardly 50 projecting parts, gravity conveyers arranged on opposite sides of said elevators with their ends spaced therefrom, and a feeding member and a discharging member respectively arranged between the gravity conveyers and elevator, said parts being adapted to permit the platforms to pass and having two complementary portions so arranged as mutually to support a package in the plane of travel of the platforms and respectively co-operating with the forwardly and rearwardly projecting parts of the latter in the transfer of the packages, each of said portions of each member having rollers and one of said portions of each member having 55 their said rollers connected and mounted for traveling and rotative movements, and means for causing the latter rollers to travel intermittently at predetermined times in the movement of the platforms, said means being arranged to be operated by a moving part of the elevator. 60

In testimony whereof I affix my signature, in presence of two witnesses.
